(57) **CLAIM**

The ornamental design for a support bracket, as shown and described.

DESCRIPTION

FIG. 1 is a perspective view of a support bracket showing my new design;

FIG. 2 is a side view thereof;

FIG. 3 is a front view thereof;

FIG. 4 is a plan view thereof;

FIG. 5 is the opposite side view thereof;

FIG. 6 is a bottom view thereof; and

FIG. 7 is a rear view thereof;

FIG. 8 is a perspective view of an alternate embodiment showing my new design;

FIG. 9 is a side view thereof;

FIG. 10 is a front view thereof;

FIG. 11 is a plan view thereof;

FIG. 12 is the opposite side view thereof;

FIG. 13 is a bottom view thereof; and,

FIG. 14 is a rear view thereof.

Any undisclosed surface area in any figure is without ornamentation.
